United States Patent Office

Des. 181,678
Patented Dec. 10, 1957

181,678

THERMOSTAT

Frank B. Roth, Richmond Heights, Mo., assignor, by
mesne assignments, to White-Rodgers Company, a cor-
poration of Delaware

Application September 21, 1956, Serial No. 43,043

Term of patent 14 years

(Cl. D52—7)

FIG. 4

FIG. 2

FIG. 1

FIG. 3

FIG. 5

Fig. 1 is a front view of a thermostat, with the hinged cover in closed position, showing my new design;

Fig. 2 is a top plan view of the thermostat shown in Fig. 1;

Fig. 3 is a front view of the thermostat with its hinged cover opened 90°;

Fig. 4 is a top view of the thermostat with its hinged cover opened 90°;

Fig. 5 is a right side view of the thermostat shown in Fig. 1.

The design for the thermostat disclosed is characterized

by the control member on the bottom having the configuration shown.

I claim:

The ornamental design for a thermostat, substantially as shown and described.
